UNITED STATES PATENT OFFICE

148,744

DESIGN FOR A COMBINATION CHAIR AND CHEST

Harold P. Bennett, West New York, N. J.

Application September 20, 1946, Serial No. 133,440

Term of patent 7 years

(Cl. D15—11)

To all whom it may concern:

Be it known that I, Harold P. Bennett, a citizen of the United States, residing at West New York, in the county of Hudson and State of New Jersey, have invented a new, original, and ornamental Design for a Combination Chair and Chest, of which the following is a specification, reference being had to the accompanying drawing, forming a part thereof.

I claim:

The ornamental design for a combination chair and chest, as shown.

HAROLD P. BENNETT.
